AGITATING APPARATUS

Richard J. Burke, Corona Del Mar, Calif.

Application July 3, 1950, Serial No. 171,892

17 Claims. (Cl. 259—1)

1

This invention relates generally to apparatus for agitating fluids or fluid entrained particles to attain various advantageous results, including in certain instances the agglomeration of such entrained particles and in other instances the intimate mixture of the substances agitated.

Though cyclon separators, electrical precipitators and the like will effectively remove entrained particles above a minimum size range from a fluid stream, the extremely small particles carried by such a stream resist separation by any of these usual expedients. To obviate this difficulty, an important object of the present invention is to provide apparatus usable in conjunction with a conventional separator to increase its efficiency of separation by agglomerating or uniting such small particles prior to the separating operation in a manner forming larger particles capable of effective removal by the separator. In certain of its aspects, the invention is particularly directed to the agglomeration of fine dust, liquid or other particles suspended in a gas, such as air.

In accordance with the invention, the minute fluid entrained particles are agglomerated by passing the fluid stream through a nest of closely spaced vibrating wire-like elements whose energy of vibration is employed to drive the particles together and cause their union or integration. Specifically, the elements are vibrated at a frequency and velocity sufficiently great that the entrained particles engaging the elements are struck off at such high velocity as to agglomerate by impact with any of the other free particles which they may strike. If the particles are not of a nature to agglomerate by impact, or if two fluids are introduced into the device rather than a single fluid carrying suspended particles, the vibrating wires then serve to uniformly disperse and intimately mix the materials in a highly effective and extremely rapid manner.

Preferably, the fluid or fluids are directed diagonally through the nest of elements, in either of the uses of the device, to assure maximum opportunity for contact of the fluids and particles with the wires. At this point, it should be mentioned, that the term "wire-like elements," as used herein, includes not only wires of circular cross section but also vibratable elongated elements of flat ribbon like design or of any other convenient cross sectional shape.

Under certain circumstances, sufficient vibration of the wire-like elements may possibly be produced by the movement of the fluid stream itself through the wires. However, I prefer to

2

provide means for positively vibrating the elements to assure the development of adequate vibrating energy to effect the desired agglomeration or mixture. For this purpose, I may employ any conventional means for vibrating the wires, as for instance an electric solenoid actuated by a pulsating direct current or alternating current of suitable frequency.

It is contemplated that the most effective vibrating frequency of the elements may vary in accordance with changes in such conditions as the rate of fluid flow or the materials handled. Consequently, I prefer to provide means for accurately controlling the frequency of vibration to produce optimum results under any given set of circumstances. As will appear, such control may be effected by either or both controlling the frequency at which the elements are driven by the vibrating power source or varying the tension and therefore the natural and harmonic frequencies of the elements. It is also noted that under certain circumstances it may be desirable to drive the elements at frequencies corresponding to the natural frequencies to which they are adjusted, while under other circumstances most satisfactory results may be attained by driving the elements at other than their natural frequencies.

When the device is employed as an agglomerator, some of the composite particles formed by agglomeration may reach a size permitting their separation by gravity as they are passing through the nest of vibratable wires. To permit such gravity separation of these relatively large particles, I may provide an outlet at the bottom of the agglomerator shell through which any separated particles are free to fall. Preferably, the walls of the shell converge downwardly beneath the nest of wires to direct the gravity separated particles into the bottom outlet. In this connection, a particular feature of the invention involves the provision of baffle means within this lower downwardly converging portion of the shell for preventing a by-passing flow of the fluid across the underside of the nest of wires.

Structurally, the wires may be supported by and between one or more pairs of members mounted in spaced relation within a shell through which the fluid stream is directed. One of the members of each pair may be mounted stationarily with respect to the shell, while the other is free for relative vibration under the influence of an actuating solenoid or other power source. Variation of the tensional force exerted on the wires is effected by adjustment of one of the mounting members relative to the other.

The above and other features and objects of the present invention will be better understood from the following detailed description of the typical embodiments illustrated in the accompanying drawing in which:

Fig. 1 is a horizontal section through a preferred form of agglomerator or mixer embodying the invention;

Fig. 2 is a vertical section through the apparatus taken on line 2—2 of Fig. 1;

Fig. 3 is an enlarged fragmentary vertical section taken on line 3—3 of Fig. 2 and showing especially the manner of mounting the end plate or member by which the wires are vibrated; and

Fig. 4 is an enlarged fragmentary transverse section taken at the powered end of the apparatus and showing a variational form of the invention.

The form of the invention shown in Figs. 1 through 3 comprises essentially a shell 10 through which the fluid passes from inlet 11 to outlet 12, a nest of closely spaced vibratable wires 13 within the shell, an electric solenoid 14 for vibrating the wires, a control device 15 for supplying to the solenoid through amplifier 16 a pulsating direct or alternating current of controllable frequency, and an outlet line 17 leading from the bottom of the shell through which some of the larger particles are discharged when the device is employed as an agglomerator.

The upper portion of shell 10 is rectangular in horizontal section, having a pair of side walls 18 and 19 and end walls 20 and 21. Fluid inlet 11 is connected into one end of a first side wall 18, while outlet 12 leads from the opposite end of the second side wall 19, so that the fluid in flowing through the shell passes diagonally across the nest of wires. The top of the shell may be closed by a suitable cover 22 adapted for removal to permit cleaning or repairing of the device. The lower portions of the side and end walls of the shell converge downwardly at 23 to form a reduced dimension bottom opening 24 connected with and leading into the bottom outlet 17. A series of baffles 25 extend longitudinally of the shell within its lower converging portion to prevent a by-passing fluid flow about the bottom of the wire nest. Lower outlet 17 may contain a suitable discharge controlling valve, as for instance butterfly type valve 26.

Wires 13 are stretched between and vibrated by a pair of relatively movable transverse rectangular plates or heads 27 and 28 positioned at the opposite ends of the shell and to which the wires are individually attached in any suitable manner. A first one of the plates 27 extends along the inside of end wall 20 of the shell, and is stationarily attached to that end wall by a number of bolts 29 carrying outer adjusting nuts 30. The opposite plate 28 is supported and guided for limited horizontal movement both longitudinally and transversely of the shell by reception of a number of pins 31 carried by the plate 25 within horizontally elongated slots 32 in the end wall. A number of coil springs 33, preferably at least four positioned at the corners of the plate 28, urge that plate toward wall 21 and in a direction away from plate 27 to longitudinally tension the wires 13. Each of these springs bears at one end against a bracket 35 projecting from the adjacent side wall of the shell and at the opposite end against the enlarged head 34 of one of the pins 31 to through it bear against the plate.

Solenoid 14 is mounted in any suitable man-

ner, as by brackets 36, to the end wall 21 of the shell. Armature 37 of the solenoid connects with a lug 34 which projects outwardly from plate 28 through a flexible fluid sealing gland 32 in the end wall 21. The control or current supplying device 15 may be of any known type adapted to supply a pulsating direct or alternating current of controllable frequency to the solenoid. Amplifier 16 increases the value of the current produced by control device 15 to a value sufficient for actuation of the solenoid and associated parts. If the solenoid is of a type adapted to positively actuate the plate in only one direction, a return spring 50 may be provided, as typically illustrated at 50.

In preparing the device for use, nuts 39 are first adjusted to vary the tension exerted by springs 33 on wires 13 and to set the wires for natural vibration at a predetermined frequency found to be correct for the particular operating conditions to be met. Controlling device 15 is then connected to a suitable source of current and adjusted to produce a pulsating direct or alternating current of a given frequency, which may in certain circumstances be the same as the frequency to which the wires are adjusted. This current, as increased in value by amplifier 16, is passed through solenoid 14 to effect the vibration of armature 37, plate 28 and wires 13.

When the device is to be used as an agglomerator, a fluid stream carrying entrained particles is introduced into the shell 10 through inlet 11 to pass diagonally across the shell and wires to outlet 12. As the wires vibrate, they strike the minute particles carried by the fluid stream and drive them at high velocity into engagement in a manner effecting their union or agglomeration into larger and more easily separated particles. Some of the enlarged particles are of sufficient weight to fall downwardly through the wires for discharge through outlet 17. The other particles pass from the device with the fluid stream for subsequent separation in their enlarged condition by any known form of separator.

If it is desired to use the device as a mixer, two or more fluids, or one or more fluids carrying solid materials, may be introduced into the shell through inlet 11. As these materials pass diagonally across the shell to the outlet, they are dispersed and intimately mixed by contact with the vibrating wires.

Fig. 4 represents a variational form of the invention in which separate groups of the wires are individually mounted and vibrated by separate pairs of plates 27 and 28 of the Fig. 1 form. Specifically, this form of the invention employs at one end of the device a plurality of horizontally elongated end plates 28a serving together the function of the plate 28 in Fig. 1. Each plate 28a is mounted separately at its opposite ends by a pin and spring mounting generally indicated at 31a and corresponding to the mounting 31, 33, 35 of Fig. 3. The plates 28a are vibratable by individual solenoids 14a, whose vibrating frequencies are individually controllable by separate electrical control devices such as that represented at 15 in Fig. 1. The stationary ends of the wires in the Fig. 4 form are mounted to a series of plates corresponding in size and shape to plates 28a and individually mounted for frequency regulating adjustment in the same manner as plate 27 in Fig. 1.

I claim:

1. Agitating apparatus of the character described comprising a shell having a fluid inlet and

a fluid outlet, a fluid passing nest of elongated vibratable wire-like elements extending in closely spaced relation between said inlet and outlet, means for vibrating the elements, means for controlling the vibrating frequencies of said last mentioned means, and means for variably longitudinally tensioning the elements to controllably vary their natural vibrating frequencies.

2. Apparatus for agglomerating particles carried by a fluid stream, comprising a shell having an inlet and an outlet between which fluid may flow along a generally horizontal path, a fluid passing nest of elongated vibratable wire-like elements extending in closely spaced relation between said inlet and outlet for agglomerating said particles as the fluid passes therethrough, the walls of said shell converging downwardly beneath said elements to a second outlet through which the heavier agglomerated particles may fall downwardly for separate discharge from the shell, and baffle means within said lower downwardly converging portion of the shell extending transversely of the horizontal path of the fluid through the shell to prevent by-passing flow of the fluid about the underside of the elements.

3. Agitating apparatus of the character described comprising a shell having a fluid inlet and a fluid outlet, a fluid passing nest of elongated vibratable wire-like elements extending in closely spaced relation between said inlet and outlet, mounting means holding corresponding first ends of said elements stationary with respect to the shell, means for exerting a yielding tensioning force on the opposite ends of said elements, and means for vibrating said opposite ends of the elements.

4. Agitating apparatus of the character described comprising a shell having a fluid inlet and a fluid outlet, a pair of members mounted in spaced relation within the shell, a fluid passing nest of elongated vibratable closely spaced wire-like elements fastened at their opposite ends to said members and extending therebetween in the path of fluid flowing from the inlet to the outlet, and means for adjusting the position of one of said members relative to the other to vary the tensioning force exerted on said elements and therefore their natural vibrating frequency.

5. Agitating apparatus of the character described comprising a shell having a fluid inlet and a fluid outlet, a pair of members positioned in spaced relation within the shell, a nest of elongated vibratable closely spaced wire-like elements fastened at their opposite ends to said members and extending therebetween in the path of fluid flowing from the inlet to the outlet, means mounting a first one of said members stationarily with respect to the shell, the second member being movable transversely of the elements, and means for vibrating said second member transversely of the elements to thereby vibrate the elements.

6. Agitating apparatus of the character described comprising a shell having a pair of end walls and a pair of opposite side walls containing an inlet and an outlet respectively, a pair of plates mounted adjacent said end walls within the shell, a fluid passing nest of elongated vibratable wirelike elements supported by and extending between said plates and through which the gas flows in passing from the inlet to the outlet, one of said plates being movable both longitudinally and transversely of the elements, a plurality of springs yieldingly urging said one plate longitudinally of the elements and away from the

other plate to maintain the elements under tension, means for relatively adjusting the plates to vary the tensioning force exerted on the elements and therefore their natural vibrative frequency, an electric solenoid operable to vibrate said one plate transversely of the elements to thereby vibrate the elements, and means for supplying electric current of controllable frequency to the solenoid to vibrate the elements at a correspondingly controllable frequency.

7. Agitating apparatus of the character described comprising a shell having a pair of opposite end walls and a pair of opposite side walls containing an inlet and an outlet respectively, a first set of plates positioned within the shell in side by side relation and near one of said end walls, a second set of side by side plates within the shell near its opposite end wall and positioned opposite the plates of said first set respectively, a fluid passing nest of elongated vibratable wire-like elements extending longitudinally within said shell, means fastening the opposite ends of separate groups of said elements to corresponding plates of said two sets, means individually mounting the plates of one set for movement both longitudinally and transversely of the elements, a plurality of springs yieldingly urging the plates of said one set longitudinally of the elements and away from the other plates to maintain the separate groups of elements under tension, means for individually relatively adjusting the opposed pairs of plates to vary the tensioning force exerted on said groups of elements and therefore their natural vibrative frequencies, a plurality of electric solenoids operable to individually vibrate the plates of said one set transversely of the elements to thereby vibrate the elements, and means for supplying electric current of individually controllable frequencies to the solenoids respectively to individually vibrate the groups elements at correspondingly controllable frequencies.

8. Agitating apparatus of the character described comprising a shell having a fluid inlet opening and a fluid outlet opening, a fluid directing conduit at the outside of the shell communicating with one of said openings, a fluid passing nest of elongated vibratable wire-like elements positioned within said shell in the path of fluid flow between said inlet and outlet, and means in addition to said elements engaging opposite ends of the individual elements and longitudinally tensioning them, different ones of said individual elements being in closely spaced relation and passing fluid therebetween.

9. Agitating apparatus of the character described comprising a shell having a fluid inlet opening and a fluid outlet opening, a fluid directing conduit at the outside of the shell communicating with one of said openings, a fluid passing nest of elongated vibratable wire-like elements positioned within said shell in the path of fluid flow between said inlet and outlet, means in addition to said elements engaging opposite ends of and longitudinally tensioning them, different ones of said individual elements being in closely spaced relation and passing fluid therebetween, and power energized means operable to vibrate said elements while they are continuously tensioned.

10. Agitating apparatus of the character described comprising a shell having a fluid inlet opening and a fluid outlet opening, a fluid directing conduit at the outside of the shell communicating with one of said openings, a fluid passing nest of elongated vibratable wire-like

elements positioned within said shell in the path of fluid flow between said inlet and outlet, means in addition to said elements engaging opposite ends of and longitudinally tensioning them, said last mentioned means being adjustable to vary the tension of said elements, different ones of said individual elements being in closely spaced relation and passing fluid therebetween, and power energized means operable to vibrate said elements while they are continuously tensioned.

11. Agitating apparatus of the character described comprising a shell having a fluid inlet opening and a fluid outlet opening, a fluid directing conduit at the outside of the shell communicating with one of said openings, a fluid passing nest of elongated vibratable wire-like elements positioned within said shell in the path of fluid flow between said inlet and outlet, means in addition to said elements engaging opposite ends of and longitudinally tensioning them, different ones of said individual elements being in closely spaced relation and passing fluid therebetween, and power energized means operable to individually vibrate separate groups of said elements while they are continuously tensioned.

12. Apparatus for agglomerating particles carried by a fluid stream comprising a shell having a fluid inlet opening and a fluid outlet opening, a pair of conduits at the outside of the shell directing fluid to and from said inlet and outlet openings respectively, a fluid passing nest of elongated vibratable wire-like elements positioned within said shell in the path of fluid flow between said inlet and outlet, and means in addition to said elements engaging opposite ends of the individual elements and longitudinally tensioning them, different ones of said individual elements being in closely spaced relation and passing fluid therebetween.

13. Agitating apparatus of the character described comprising a shell having a fluid inlet opening and a fluid outlet opening, a fluid directing conduit at the outside of the shell communicating with one of said openings, a fluid passing nest of elongated vibratable wire-like elements positioned within said shell in the path of fluid flow between said inlet and outlet, means in addition to said elements engaging opposite ends of the individual elements and longitudinally tensioning them, different ones of said individual elements being in closely spaced relation and passing fluid therebetween, power energized means operable to vibrate said elements while they are continuously tensioned, and control means for controllably varying the vibrating frequency of said last mentioned means.

14. Agitating apparatus of the character described comprising a shell having a fluid inlet opening and a fluid outlet opening, a fluid directing conduit at the outside of the shell communicating with one of said openings, a fluid passing nest of elongated vibratable wire-like elements positioned within said shell in the path

5 of fluid flow between said inlet and outlet, means in addition to said elements engaging opposite ends of the individual elements and longitudinally tensioning them, different ones of said individual elements being in closely spaced generally parallel and side by side relation and passing fluid therebetween.

15. Mixing apparatus comprising a shell adapted to contain materials to be mixed and having an inlet through which said materials are admitted thereto, a fluid passing nest of elongated vibratable wire-like elements positioned within said shell in the path of fluid flow between said inlet and outlet, means in addition to said elements engaging opposite ends of the individual elements and longitudinally tensioning them, different ones of said individual elements being in closely spaced relation and passing fluid therebetween, and power energized means operable to vibrate said elements while they are continuously tensioned.

16. Agitating apparatus of the character described comprising a shell having a fluid inlet and a fluid outlet, a fluid passing nest of elongated vibratable wire-like elements positioned within said shell in the path of fluid flow between said inlet and said outlet, mounting members in addition to said elements engaging opposite ends of the individual elements and longitudinally tensioning them, different ones of said individual elements being in closely spaced relation and passing fluid therebetween, and a power energized vibrator operable to vibrate said elements while they are continuously tensioned by said mounting members.

17. Agitating apparatus of the character described comprising a shell having a fluid inlet and a fluid outlet, a fluid passing nest of elongated vibratable wire-like elements positioned within said shell in the path of fluid flow between said inlet and said outlet, mounting members in addition to said elements engaging opposite ends of the individual elements and longitudinally tensioning them, different ones of said individual elements being in closely spaced relation and passing fluid therebetween, and an electrically energized vibrator operable to vibrate said elements while they are continuously tensioned by said mounting members.
